(57) **CLAIM**

The ornamental design for a resin wicker panel, as shown and described.

DESCRIPTION

FIG. 1 is a perspective view of the resin wicker panel of the present invention;

FIG. 2 is a front view thereof;

FIG. 3 is a top view thereof;

FIG. 4 is a left side view thereof;

FIG. 5 is a right side view thereof; and,

FIG. 6 is a bottom view thereof.

The reverse side of the resin wicker panel is not claimed. The broken lines representing the reverse side of the design form no part of the claimed design.
